(57) **CLAIM**

The ornamental design for a display fixture, substantially as shown and described.

DESCRIPTION

FIG. 1 is a perspective view of a display fixture;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof;

FIG. 7 is a bottom plan view thereof;

FIG. 8 is another perspective view thereof; and,

FIG. 9 is another perspective shown without environment.

The shelving units on both sides of the display fixture are symmetrical with respect to shape, configuration, and ornamental design.

The broken lines showing is included for the purpose of illustrating environment and forms no part of the claimed design.
